PROJECTION VIEWER

Joseph H. Wally, Jr., Shawnee Mission, Kans., assignor to
Opti-Copy, Inc., Kansas City, Mo., a corporation of
Missouri

Filed May 5, 1965, Ser. No. 85,113

Term of patent 14 years

(Cl. D61—1)

FIG. 1

FIG. 3

FIG. 2

FIG. 4

FIGURE 1 is a front and left side perspective view of a projection viewer showing my new design;

FIGURE 2 is an elevational view of the right side thereof;

FIGURE 3 is a rear elevational view thereof; and

FIGURE 4 is a top plan view of the projection viewer. The dominant features of my design for a projection viewer reside in the portions shown in full lines.

I claim:

The ornamental design for a projection viewer, substantially as shown and described.
